US00D614769S

(12) **United States Design Patent**
Vogel et al.

(10) **Patent No.:** US D614,769 S
(45) **Date of Patent:** ** Apr. 27, 2010

(54) **INTERFACE**

(75) Inventors: Urs Vogel, Sehaffhaus (CH); Dieter Huels, Stockach (DE)

(73) Assignee: Karl Storz GmbH & Co. KG (DE)

(**) Term: 14 Years

(21) Appl. No.: 29/318,005

(22) Filed: May 12, 2008

(30) **Foreign Application Priority Data**

Nov. 12, 2007 (EM) 000824495

(51) LOC (9) Cl. 24-02

(52) U.S. Cl. D24/138

(58) **Field of Classification Search** D24/133, D24/135, 176, 152, 156, 140, 141, 143, 137, D24/138, 160; 600/206, 214, 164, 157, 156, 600/200, 113, 135, 138, 121, 131, 153; 606/191, 606/196, 197, 198; D8/107

See application file for complete search history.
